UNITED STATES PATENT OFFICE.

ALBERT BROSCHÉK, OF HAMBURG, GERMANY.

INTAGLIO-PRINTING MACHINE.

1,171,314.

Specification of Letters Patent.

Patented Feb. 8, 1916.

Application filed October 2, 1912. Serial No. 723,531.

To all whom it may concern:

Be it known that I, ALBERT BROSCHÉK, of Hamburg, a subject of the King of Prussia, and whose post-office address is 38-50 5 Grosse Bleichen, Hamburg, German Empire, have invented new and useful Improvements in or Relating to Intaglio-Printing Machines, of which the following is a specification.

0 This invention relates to intaglio printing machines, particularly those for producing large editions of illustrated papers and magazines of any desired size and having a large number of pages.

15 The object of this invention is to produce such papers or magazines in a single machine in which the intaglio printing process, cutting, folding and binding of the papers is effected in one operation.

20 Rotary intaglio perfecting machines printing from engraved copper cylinders hitherto constructed are always combined with "fixed size" rotary typographic relief printing machines in cases where the paper webs printed thereby are subsequently fed to a folding apparatus. The intaglio machine in this case produces the illustrations and the "fixed size" rotary machine produces the letter-press. Intaglio machines for

30 printing illustrations and letter press on both sides of endless webs, which are then cut up into single sheets and distributed by a folding apparatus have not hitherto been made, owing to the great difficulties in their construction due to the intaglio printing process.

35 As is well known, printing in such machines is effected from engraved copper surfaces mechanically connected to or deposited by an electrolytic process on cylinders of special construction. To reduce the considerable loss of time and consequent expense, such copper surfaces when once connected to the cylinders are left on as long as possible, and as soon as one edition is

45 finished the picture engraved on the copper is removed by grinding and in this way the effective diameter of the cylinder tends constantly to reduce. Up to a certain point this reduction can be neglected, but if it is continued the difference in the speed of the paper web with reference to that at which the folding apparatus is designed to work becomes excessive, and it is then impossible to deal with the web in the folding apparatus. This difficulty can only be overcome

by so arranging the cutting and folding apparatus that it can receive and deal with endless webs at whatever speed they are introduced.

All folding apparatus hitherto known in 60 which the work is supplied in an endless web are intended for a fixed size *i. e.* they only cut and fold sheets of given lengths of which the greatest length that can be dealt with is an exact multiple. The paper is generally supplied to the folding apparatus at 65 the same speed which corresponds to the circumferential speed of all its members. In intaglio printing machines however the circumstances are different since the speed 70 at which the web advances changes with each edition that is printed, not only for a different size of sheet, but also when the same size is to be supplied, owing to the cylinders having to be ground for each new form as 75 above described and thus being reduced in diameter. Thus the endless paper webs which leave the printing mechanism at different speeds have to enter the cutting and folding apparatus which work with a constant circumferential speed. Preferably the same means are employed for cutting off 80 single sheets as are used in the so-called "all-size" machines.

According to this invention the web, 85 which is printed on both sides in the intaglio printing machine before reaching the cutting cylinders, is passed between rolls the circumferential speed of which is 90 brought into exact accordance with that of the form cylinders by means of some known mechanism such as change speed gearing. In the present case however the feed rolls for the variable cutting cylinders are arranged 95 between the printing mechanisms and cutting cylinders or the folding apparatus for such cutting cylinders and are not, as in the "all-size" machines above mentioned disposed between the roll of paper and the cutting cylinders or printing mechanism to 100 which the paper is then delivered.

According to this invention the feed rolls which rotate at the same speed as the form cylinders, carry the paper web between the cutting cylinders into a system of bands or tapes leading to the folding cylinders. The cutting cylinders are therefore constructed like the so-called "all-size" cutting cylinders *i. e.* they do not fit closely together but have a space or gap through which the web 110

is free to pass. At each revolution they cut from the endless web a sheet the length of which corresponds to the speed of the sheet which is entering. Only at that moment is the sheet taken over by the folding apparatus and folded in the required manner.

An intaglio printing machine according to this invention is diagrammatically illustrated by way of example in the accompanying drawings, in which,

Figure 1^a is a vertical longitudinal sectional view, partly diagrammatic, of part of a machine embodying my invention, and 15 Fig. 1^b is a similar view of the other part of said machine; the two views taken together representing the whole machine. Fig. 2 is an enlarged sectional view of two coöperating folding cylinders.

20 The paper passes from the reel 1 through the moistening or damping apparatus 0 thence into the mechanism for intaglio printing on the face side consisting of the intaglio printing cylinder 2, provided in 25 known manner with an engraved copper mantle and with a doctor, counter-cylinder 6 and rubber roller 4, thence over guide rollers into the perfecting mechanism for printing on the reverse side having perfecting 30 intaglio printing cylinder 3, counter-cylinder 7 and rubber roller 5. The web then passes through the circular cutter 21 for longitudinal cutting and thence either directly into the feed rollers 10 11 (driven at 35 the speed corresponding to the diameter of the cylinders 2 and 3) of the "all-size" cross-cutting cylinders 8, 9 *i. e.* those which allow the paper web to pass freely, or through the feed rollers 22 over the turning over rods 40 23 by means of which the cut webs are placed on the top of each other in front of the "all-size" cutting apparatus. From the latter the cut sheets pass through a system of bands or tapes passing over the rollers 45 24 where they are to be placed flat on the delivery table 20. If instead of this an illustrated paper, for instance of eight pages of large size is to be produced in which the webs cut into two strips by the longitudinal 50 cutter 21 and placed in two superimposed layers by means of the turning over rods 23, they pass from the variable cutting apparatus 8 and 9, which has cut off sheets of the length of two pages, between the variable 55 transverse folding cylinders 13 14 in order there to receive the first transverse folding. If the newspaper or periodical is to be delivered bound, the transversely folded sheets pass from the folding cylinder 14 60 over the binding cylinder 12 so as to be folded again transversely between the cylinder 14 and cylinder 15, that is to say the third variable folding cylinder. Thence the paper, transversely folded twice and 65 bound, passes into the longitudinal folder 17

and 18 and thence into a fan-like discharge 19. If binding is not required, the newspapers pass from 13, 14 direct to 14, 15.

The change speed gear for driving the feed rollers 10, 11 with a speed corresponding to the varying diameter of the printing cylinders 2 and 3 consists of 4 wheels 91, 111, 112 and 113 changeable in a well known manner for the purpose to give the cylinder 11 the desired circumferential speed.

24 are the nipping rolls of the folding apparatus.

As soon as the cutting cylinders 8 and 9 have perforated the paper web the latter is ripped off by means of the nipping rolls 24, 80 and the separated sheet is caught at the rolls 243 by the grippers 132 of the cylinder 13. Then the further operation may vary according to the circumstances. Either the grippers 132 of the cylinder 13 open after a 85 certain number of revolutions and deliver the sheets collected on cylinder 13 to the band system 201, a rake 202 laying the sheets onto the table 20, or the grippers 132 deliver the single sheets to the folding knife 131 90 folding the sheet into the cylinder 14, the folding blade 141 catching the sheet and passing it along the binding cylinder 12, the binding device 121 binding the folded sheets by one or more wire staples, whereupon the folding knife 142 folds the sheets into the cylinder 15. From this cylinder, the folded and bound sheets pass through the rotating fan delivery 16 or through the band system 181 between two rollers 18 and 100 95 the rocking folding knife 17, whereupon the fan 19 lays the longitudinally folded sheets onto the delivery band 161. If no longitudinal folding is required the fan 16 delivers the sheets immediately onto the delivery 105 band 161. The members 131 and 132 of the cylinder 13 and the members 141 and 142 are adjustable relatively to each other as shown in Fig. 2.

For illustrated newspapers of smaller 110 variable size, the operation is as follows:— For an eight page newspaper, the web, after it has passed the two printing mechanisms is longitudinally divided in the longitudinal cutter 21 into three strips, whereupon these 115 three adjoining strips are cut by the variable cutting gear 8 and 9 into sheets of four page length. These sheets are then transversely folded for the first time between 13 and 14 and at the same time cut at the fold, the 120 folding cylinder 13 being arranged in the well known manner as a cutting cylinder. Thereupon binding is effected between 12 and 14, and then the bound edge is folded for the second time between 14 and 15 and 125 delivered through the fan-like discharge 16. If the same newspaper is to be supplied in sixteen pages, the printed endless web is longitudinally divided by the longitudinal cutter 21 into two strips, one of which con- 130

tinues to advance in a straight path while the second one is placed on the first by the turning over rods 23. The rest of the operation is the same as in the case of eight pages.

5 If the same paper is to be supplied in twenty four pages it is divided by the longitudinal cutter 21 into three strips and two of the same are placed by the turning over rod 23 on the third strip, the process being the 10 same as in the case of eight pages. For changing the size the copper cylinders of the two printing mechanisms are exchanged and the speed gear for the feed rollers of the variable cutting cylinders adjusted accordingly.

15 What I do claim as my invention, and desire to secure by Letters Patent of the United States, is:—

1. The combination with suitable intaglio 20 perfecting web printing mechanism, and suitable cutting and folding mechanism, of

adjustable compensating web feeding mechanisms arranged between said printing mechanism and said cutting and folding mechanism.

2. A machine of the character described, comprising in combination a pair of intaglio perfecting web printing couples, a sheet folding mechanism, cutting mechanism for separating the web into sheets to be folded 30 and adjustable web feeding mechanism, adapted to maintain the speed of the sheet entering the cutting mechanism in conformity with the surface speed of said intaglio printing couples.

35 In testimony whereof I have hereunto set my hand in presence of two subscribing witnesses.

ALBERT BROSCHEK.
